(57) **CLAIM**

The ornamental design for a slipper, as shown and described.

DESCRIPTION

FIG. 1 is a top, front, left-side perspective view of a slipper according to our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a top, front, left-side perspective view of a second embodiment thereof;

FIG. 9 is a front elevation view of FIG. 8;

FIG. 10 is a rear elevation view of FIG. 8;

FIG. 11 is a left-side elevation view of FIG. 8;

FIG. 12 is a right-side elevation view of FIG. 8;

FIG. 13 is a top plan view of FIG. 8; and,

FIG. 14 is a bottom plan view of FIG. 8.

The dashed lines shown around the eyelets of the slipper in FIGS. 1, 2, 4–6, and in the bottom view of the slipper in FIG. 7 represent stitching and forms part of the claimed design. All other dashed lines represent unclaimed portions of the slipper and form no part of the claimed design.
